Augustus M. Henry

UNITED STATES PATENT OFFICE.

HENRY A. HAYDEN, OF JERSEY CITY, NEW JERSEY, ASSIGNOR TO MOSES H. HARRIS,
OF NEW YORK, N. Y.

EYEGLASS POLISHER-CONTAINER.

1,242,187.

Specification of Letters Patent. Patented Oct. 9, 1917.

Application filed August 9, 1915. Serial No. 44,403.

To all whom it may concern:

Be it known that I, HENRY A. HAYDEN, a citizen of the United States, and a resident of Jersey City, in the county of Hudson and State of New Jersey, have invented 5 certain new and useful Improvements in Eyeglass Polisher-Containers, of which the following is a specification.

Broadly, the present invention relates to 10 containers. More particularly, there is presented as a new article of manufacture, and as an embodiment of the invention, a container-polisher for eye-glasses which, while flexible in those respects which lead to important advantages, is rigidified in certain 15 particulars which lead to other important advantages.

In connection with the disclosed embodiment, an embodiment at present preferred:—

(A) Some of the advantages inherent in the feature of flexibility may be mentioned as (1) utility of the container or parts thereof as a lens-polisher; (2) prevention of accidental loss of the contents from an open-mouthed container; (3) prevention of loss of the container itself from a pocket or the like even when the top-mouth of the pocket is downturned; and (4) light weight, cheapness and convenience of use.

(B) Some of the advantages inherent in the rigidity above mentioned may be expressed as (1) absolute insurance against lens-breakage; (2) resilient maintenance in a predetermined condition of the otherwise flexible container; (3) direct aid in lens-polishing; and (4) the presence of manipulable means for rendering, by being functional to flare or "round" the mouth of 40 the container, easy and instantaneous the insertion into the container of a pair of eyeglasses.

The advantages mentioned above in paragraphs (A) and (B), as well as certain 45 other advantages hereinafter obvious or pointed out, will be clear after a study of the contents of this specification.

In the accompanying drawing,

Figure 1 is a rear elevation of said embodiment;

Fig. 2 is a side elevation thereof;

Fig. 3 is a vertical sectional view, taken on the line 3—3 of Fig. 1; and

Fig. 4 is a vertical sectional view, taken on the line 4—4 of Fig. 2, certain of the 55 parts being broken away additionally in aid of clarity.

It should be noted that when hereinafter the term "here" is employed, the reference is merely to an incidental feature of the 60 illustrative embodiment now to be described; the scope of the invention being defined by the claims.

The reference numerals 1, 2, 3 and 4 represent respectively four cuttings of flexible 65 material which are sewn together as indicated at 5 to constitute the container proper as here disclosed. Here cuttings 1 and 2 are of chamois, and cuttings 3 and 4 are of velveteen.

Before a mouth-binding tape 6 is stitched into place as shown, a rigidifying bow 7 is inserted into the bag established by the joined cuttings 1, 2, 3 and 4. Then, when here the tape 6 is stitched into place, the 75 bow's termini 7^a, and hence the bow itself, are anchored as illustrated in Figs. 3 and 4. Of course the termini of the bow may be apertured or perforated so as not to interfere with the stitching in place of the entire 80 length of tape 6. Or said stitching may merely sew in place all subdivisions of the length of tape 6, except the subdivisions which cross said termini.

The bow 7 is preferably made of a flat 85 length of spring metal, treated to or capable of forestalling rust. The bowl 7^b (Fig. 4) of the bow is here merely a naturally resiliently urged curve, due to the confinement of the bow within the bag after the termini 7^a 90 are anchored as aforesaid, and which tends to establish the bag normally flattened as shown in Figs. 1 and 2. Here also a pair of opposite and symmetrically arranged (relatively of the showing of Fig. 4) bends 95 7^c are reentrantly formed in the U-legs of bow 7, so as normally, and despite the spring material of which the bow is made, to yieldably persist as shown in Fig. 4.

Mounted here upon the rear of the bag 100 are three strips of preferably flexible material 8, 9 and 10. Strip 8 may be of chamois,

strip 9 also of chamois, and strip 10 of leather. The strips are superposed one on another and are stitched to the bag as indicated at 8^a and 8^b in Fig. 1. Here stitching 5 8^a is at the same time a part of the stitching that sews tape 6 to the bag.

While it is here desirable that the main 10 portions of strips 8 and 9 and of cutting 1 each be freely movable relatively of any of the others, for lens-polishing, strip 10 may have its central portion glued or otherwise 15 affixed to strip 9. In any event, the outer surface of strip 10, provided the same be made of leather or other suitable material, may have printed thereon, say in gilt letters, 20 the name of the owner, an advertisement, or other desired indicia.

A ring 12, to which may be tied a portion 25 of an eye-glass cord 11, and which ring is representative of any suitable attaching device, is here stitched to the bag as shown 30 in Fig. 1.

A brief examination of the drawing, in 35 the light of the contemplated advantages mentioned in paragraphs (A) and (B) above, will make clear the presence of at least those advantages. The bow 7, at present viewed as the most important feature 40 of the invention (when combined with the flexible bag), is valuable in a multitude of ways. It will be noted that the flatness of the strip constituting here the bow is always at right angles to the plane of the lens-faces when a pair of eye-glasses is stored in 45 the bag. While the generally irregular conformation of the bag, resulting from the presence therein of said eye-glasses, cooperates with the preferably plushlike outer surface of the bag material to absolutely 50 prevent the bag from dropping from an overturned open pocket, and while the same characteristics, aided by the pressure of the bends 7° against the periphery of the mouth-adjacent lens, prevents absolutely the eye-glasses from dropping from the container 55 when placed upside down, the presence of the bow always prevents breakage of the bag's contents, for the bag cannot be bent except within the plane of the lens-faces and never across such plane. Quick and easy 60 insertion of a pair of eye-glasses into the bag is also rendered possible by the presence of bow 7, for upon slightly pressing the U-legs of the latter toward each other the mouth of the bag is "rounded" or "opened" 65 to the desired degree. The presence of bow 7 aids, also, in a polishing operation, by maintaining the bag yieldably spread into flatness, whether a lens is being polished 70 between cuttings 1 and 2, between cutting 1 and strip 8, or between strips 8 and 9. A further great advantage results from the 75 general structure, due to the fact that a very

small piece of chamois, so small, indeed, 80 that a collection of such pieces may be purchased as chamois-scrap, when affixed to or forming part of a bow-spread bag as just described, is quite as efficient for polishing purposes as a large chamois sheet or a subdivision thereof of the ordinarily used dimensions. And chamois-scrap is purchasable at such a low price that at present it is 85 practically a drug on the market, whereas sheet chamois is highly expensive.

The ring 12 or a suitable substitute may 90 serve to permit the container to be attached to an eye-glass or other cord 11, so that the container may even be worn when coat and vest are off, a simple twist of the cord about a shirt-button allowing the container to depend either visibly outside or invisibly inside the shirt. One advantage of this, and due in no small measure to the lightness and lack of bulk of the container resulting from 95 its peculiar construction, is the avoidance of any necessity for placing the eye-glass cord around a wearer's neck, a very frequent situation which just as frequently leads to a breaking of the glasses.

Obviously, the generic idea of the invention may with great latitude otherwise be employed, as, for instance, in a type of eye-glass container composed mainly of two flaps, each constructed of some flexible material, arranged like the leaves of a book, 95 one of the flaps having attached to and arranged about its bounding edges a flat up-standing strip of metal or of like comparatively rigid material, and the other flap being closable over the first flap and its 100 strip of metal and buttonable to said first flap, whereby there may be safely stored between the two flaps a pair of eye-glasses. Here, too, it will be noticed, the two essential elements, to wit, a generally flexible-walled container and a stiffening skeleton-strip, are both employed.

I claim:

1. A device of the class described, including, in combination, a flat open-topped bag 110 of flexible material, and a flat stiffener-strip located within the bag and while inflexible across the plane of the flat of the bag resiliently flexible within said plane, said strip being intermediately bent into a reentrant 115 angle which constitutes a yieldable nose extending within the bag to yieldably narrow the width of the bag intermediate the top and bottom thereof.

2. A device of the class described, including, in combination, a flat open-topped bag 120 of flexible material, and a flat stiffener-strip located within the bag and lying in substantial coincidence with the closed periphery of the bag and inflexible across the plane 125 of the bag, said strip being substantially

U-shaped in the said plane and each leg of the U being intermediately provided with a reentrant bend, the crests of the bends extending toward each other to narrow the width of the bag intermediate the top and bottom thereof.

Signed at New York, in the county of

New York and State of New York, this 29th day of July, A. D. 1915.

HENRY A. HAYDEN.

Witnesses:

A. M. HENRY,
